UNITED STATES PATENT OFFICE.

ABRAHAM L. MOLER, OF RICHMOND, VIRGINIA, ASSIGNOR OF ONE-HALF TO JOHN W. SMALL, OF RICHMOND, VIRGINIA.

LUBRICATING DEVICE.

Application filed May 15, 1926. Serial No. 109,229.

This invention relates to lubricating devices.

One object of the invention is to provide an improved journal lubricating device especially adapted for use in connection with locomotive driving boxes, said device including a detachable grease cellar provided with a central compartment designed for the detachable reception of automatically operable grease distributing means, together with side extensions adapted to fit into the driving box and so arranged as to provide grease pockets concentrically disposed with reference to said journal at either side of said central compartment, and also providing air circulating passages about the journal to cool the same when said grease cellar is in operative position in the driving box.

Other and further objects of the invention will more clearly appear from the description and claims hereinafter following.

In the drawings, Fig. 1 is an end elevation of a grease cellar embodying my invention, showing the same applied to a driving box. Fig. 2 is a vertical, sectional view of the grease cellar substantially on the line 2—2 of Fig. 1, and Fig. 3 is a vertical, sectional view of the grease cellar substantially on the line 3—3 of Fig. 2.

Referring to Fig. 1 of the drawings, a driving box and journal of the usual type are illustrated, the driving box being provided with spaced jaws 10—10, defining a U-shaped opening adapted for the reception of the journal 11, the usual brass or liner 12 being provided against which the journal 11 bears. The lower ends of the jaws 10—10 are provided with bores for the reception of securing bolts for holding the grease cellar in proper position between the jaws 10—10 of the driving box.

The grease cellar or dispensing device is preferably made up in the form of a casting having a bottom wall 13, vertical side walls 14—14, one integral end wall 15, and a movable end wall 16. The end wall 16 is provided with spaced slots 17—17 through which extend headed screws 18—18 into the body portion of the cellar, the construction being such that loosening of the screws permits dropping of the plate 16, which can be again elevated and secured by the screws in a position over the end of the central compartment defined by the side walls 14—14, and end wall 15. The top edges of the end

walls 15 and 16 are arranged concentrically with reference to the curvature of the journal 11, and when the cellar is in operative position the top edges of said end walls are slightly spaced from said journal. The central chamber is adapted for the detachable reception of an automatic dispensing device, the side walls 14—14 being provided with offsets 19—19 for cooperation therewith in a manner hereinafter described.

Disposed in the central compartment is an arcuate plate 20 provided with vertically disposed flanges 21—21 which fit into the offsets 19—19 of the side walls and cooperate with said offsets to limit the downward movement of the plate 20. The plate 20 is adapted to have its arcuate face bear against the journal 11, said arcuate portion being provided with a plurality of openings 22 through which lubricant may be passed to the journal. Mounted for cooperation with the plate 20 is a follower plate 23 on which a grease cake 24 rests, the follower plate 23 being provided with spring seats 25—25 on its under-surface, which are in alinement with springs 26—26 which bear against the follower plate 23 to normally force the same in an upward direction. Grease gauges 27—27 are secured at their upper ends to the follower plate 23 and project through openings 28 in the bottom wall 13 of the grease cellar so that anyone examining the cellar to ascertain whether or not it needs a new cake of grease can easily determine this by inspection of the gauge rods 27—27.

The central chambered portion of the grease cellar is of relatively small extent when compared to the distance between the jaws 10—10 of the driving box, and the remainder of the space between the jaws and the central chambered portion is taken up by an arrangement which provides for additional grease pockets disposed about the journal and for circulatory air passages about the journal, while at the same time permitting a nice fit of the cellar between the jaws 10—10 of the driving box and without interfering with the free independent removal, replacement and operation of the automatic grease dispensing device.

Preferably formed integrally with the upper portions of the side walls 14—14, and somewhat below the top edges thereof, at each side of the central compartment, are curved walls 29—29, which adjacent their

2
 outer extremities are arranged vertically as indicated at 30—30, and each of said walls terminates in a horizontally disposed flange 31, the portions 30 being of a width substantially corresponding to the distance between the opposite engaging faces of the jaws 10—10. At each end of the cellar, the walls 29—29, and walls 30—30 merge into the end walls 32—32, the top edges of said latter walls being concentrically disposed with reference to the journal 10 and normally spaced therefrom as shown, this construction providing a shallow grease collecting pocket at each side of the central chamber, which grease pockets are concentrically arranged with reference to the journal 11.

Preferably formed at the lower four corners of the walls 14—14 are lateral extensions or lugs 33—33, said extensions providing base portions having their outer faces spaced apart a distance to fit snugly between the inner faces of the jaws 10—10 of the driving box, the portions of the cellar between the grease pockets and the extensions 33 being cut out at each side of the cellar as indicated at 34—34, so that the cellar when in position in the driving box will have air passages which extend closely adjacent to the central compartment of the cellar and are disposed about said concentric shallow grease pockets to provide for circulation of air and cooling of the journal. Webs 35—35 are extended laterally to each side of the central chamber walls 14—14 to increase the strength of the device. The cellar is held in position between the jaws of the driving box by means of suitable pins indicated at 36, which project through the extensions upon the lower portion of the cellar and through the bores provided in the lower ends of the jaws 10—10 of the driving box.

In practice the grease cake 24 is pressed upwardly by the spring follower plate 23, holding grease cap 20 in contact with the journal, the revolving journal forming a suction which draws the needed amount of grease through the perforations in the plate 20, and this grease keeps the journal constantly lubricated. When the grease cake has been consumed, this fact is indicated by the position of the gauges 27—27, and by loosening the screws 18—18, the plate 16 may be dropped so as to give access to the central compartment, and the plate 20 may be slid longitudinally out of the central compartment and a new grease cake inserted in position, after which the plate 16 may be elevated and the screws 18—18 again tightened. When it is desired to remove the journal 11 from the box, the grease cellar may be readily detached by withdrawing the bolts or pins 36 which permits the grease cellar to be withdrawn from the driving box.

65 The concentrically disposed shallow side

grease pockets have an important function in catching and retaining waste grease until it becomes advisable to clean out the waste grease, and due to the arrangement of said pockets and the remaining portions of the 70 grease cellar at opposite sides of the central compartment, when the grease cellar is placed in position between the jaws 10—10 of the driving box, large open passages are provided which enable the air to circulate 75 freely both vertically and longitudinally in close proximity to the journal and so cool the same, the arrangement being such that foreign material is effectively excluded while permitting the desirable circulation of 80 air about the parts.

85 While I have herein shown and described what I now consider the preferred manner of carrying out the invention, the same is merely illustrative, and I contemplate all changes and modifications that come within the scope of the claims appended hereto.

I claim:

1. A detachable cellar for a locomotive driving box having the usual depending spaced jaws, said cellar including: a centrally disposed, narrow, relatively deep chamber; two side chambers each relatively shallow, partitions separating said side chambers from the central chamber whereby lubricant may be dispensed from the central chamber and carried over lubricant collected in the side chambers, spaces being left at each side of said central chamber and beneath the side chambers, said 95 spaces being adapted for the circulation of currents of air therein when the cellar is between the jaws of the driving box.

2. A detachable cellar for a locomotive driving box having the usual depending spaced jaws, said cellar having: a centrally disposed, relatively deep chamber; two relatively shallow side chambers, spaces being left at each side of said central chamber and beneath the side chambers, said spaces being adapted for the circulation of air therein when the cellar is between the jaws of the driving box, said cellar being provided with corner lugs at the bottom thereof extended laterally from the central chamber 105 and adapted to cooperate with the driving box to position the cellar, said corner lugs being separated longitudinally of the cellar.

3. A detachable cellar for a locomotive driving box, said cellar having: a centrally disposed relatively deep chamber; two side chambers each relatively shallow, said chambers being separate and distinct from each other, said cellar having integral walls at one set of ends of said chambers, spaces being provided at each side of the central chamber and beneath the side chambers for the circulation of cooling currents of air; and a displaceable end wall plate at the opposite end of said central chamber whereby 115

lubricant dispensing means may be inserted and removed endwise from said central chamber, said plate being of restricted width whereby to leave the ends of said spaces unobstructed.

4. A detachable cellar for a locomotive driving box comprising: a casting having a central, narrow deep chamber with vertical side walls, curved walls extending laterally and upwardly from each of said side walls and united to the latter at points slightly below the top edges thereof whereby to provide relatively shallow side chambers, said side walls of the central chamber being arranged to act as guides for a grease-dispensing plate, said casting having integral formations at the lower part thereof adapted to fit portions of the driving box.

5. A detachable cellar for a locomotive driving box having the usual depending spaced jaws, said cellar having: a centrally disposed chamber; two side chambers each relatively shallow, said side chambers being separated from the central chamber by partitions, spaces being left at each side of said central chamber and beneath the side chambers, said spaces being adapted for the circulation of currents of air therein when the cellar is between the jaws of the driving box; a perforated grease-dispensing plate disposed in said central chamber; and a resiliently impelled follower also disposed in said central chamber.

6. A detachable cellar for a locomotive driving box having the usual depending spaced jaws, said cellar including: a casting having four bottom corner lugs adapted to fit within said spaced jaws, each pair of lugs on each side being separated lengthwise of the cellar and said casting having a centrally disposed, longitudinally extending, relatively narrow bottom wall and sections

extended upwardly therefrom, said sections having the uppermost edges thereof disposed outwardly in a line approximately vertically above the outermost faces of said lugs, whereby air may circulate upwardly between said pairs of lugs on either side of said narrow bottom wall when the cellar is in position between the jaws of the driving box; a relatively narrow grease-dispensing plate; a relatively narrow grease follower plate, said plates being disposed above said bottom wall and approximately coextensive in length therewith, whereby grease may be dispensed over a relatively narrow arc of the journal; and a displaceable end plate mounted on the inner end of the casting whereby access may be had to the grease chamber for insertion of a supply of grease.

7. A detachable cellar for a locomotive driving box having the usual depending spaced jaws, said cellar including: a casting having a centrally disposed bottom wall appreciably narrower than the space between said jaws, integrally formed side walls extending vertically from the side edges of said bottom wall, and webs integrally formed with said side walls and extending outwardly and upwardly therefrom to the uppermost points of the casting, said casting having also four corner lugs at the bottom thereof extended outwardly so as to fit within said jaws, the two lugs on each side being spaced apart longitudinally of the cellar whereby air may pass vertically upwardly in contact with said side walls and webs; an end plate attached to said casting; a grease-dispensing plate; and means to maintain said plate in a position centrally of the cellar.

In witness that I claim the foregoing I have hereunto subscribed my name, May 5th, 1926.

ABRAHAM L. MOLER.
